UNITED STATES PATENT OFFICE

GENE HERZ, OF CHICAGO, ILLINOIS, ASSIGNOR TO HERZ BED COMPANY, OF CHICAGO, ILLINOIS, A CORPORATION OF ILLINOIS

HEADREST FOR BEDS

Application filed April 10, 1926. Serial No. 101,023.

My invention relates to a head-rest for beds and the like, and more particularly to improved means for retaining the head-rest in elevated or operative position.

The principal object of my invention is to provide a retaining device which is simple in construction, cheap to manufacture, readily secured to the bed, and effective in operation.

Another object of my invention is to provide a novel retaining device adapted to permit ready angular adjustment of the head-rest so that the head-rest may be adjusted to different degrees of inclination to suit the wishes or comfort of the user.

More particularly, I employ a retaining or holding device formed of wire adapted to rest upon and be secured to the spring structure, whether consisting of the usual coiled bed springs or flexible link fabric, the wire being provided with a hook with which a bail mounted on the head-rest is adapted to engage to hold the head-rest in elevated position. Two or more hooks may be provided to allow the desired angularity of adjustment of the head-rest.

Various other features of advantage and utility of my construction will be apparent from the description hereinafter given in conjunction with the drawings.

Of said drawings, Fig. 1 is a top plan view of one end of a bed or bed-section, showing my invention applied thereto; Fig. 2 is a fragmentary plan view showing a modification of the retaining device; Fig. 3 is a side view of the end of the bed, shown in Fig. 1, with the head-rest in elevated position, and Fig. 4 is a top plan view of one end of a bed having the usual coiled bed springs and shows my invention applied thereto.

Referring to Figures 1 and 3, the bed comprises suitable end structures having top cross rails 5, only the one at the head being shown in these views. The spring supporting means upon which the usual mattress is mounted, comprises a wire fabric of the well-known link type, which consists of cross wires 6 and longitudinal wires 7 having their ends hooked about the rings 8, the rings 50 at the ends of the wire fabric being connected

to the rails 5 by the usual coil springs 9, as is customary in the art. Near each side of the spring fabric is a flexible flat strip 11, connected at its ends to springs 12 which are like the springs 9.

The head-rest 13 comprises a thin flat strip of metal bent into a U-formation to provide legs 14 and an upper cross member 15. The legs 14 are connected by a cross-slat 16 and a thin flat strip 17 is connected at its ends to the centers of the member 15 and slat 16. Secured to the ends of the legs 14 are eyes 18 which rest upon the strips 11 and through which project two of the cross links 6 for pivoting the head-rest to the wire fabric. If desired, the head-rest may be pivoted directly to the strips 11. A U-shaped supporting member or bail 20 for the head-rest has latterly extending ends 19 projecting through apertures formed in lugs 14^a riveted or otherwise secured to the arms 14.

The retaining device for cooperating with the bail 20 to support the head-rest in elevated position, comprises a wire 21 which is bent to form a V and to provide integral eyes 22 at its ends and a hook 23 at the point of the V. The eyes 22 engage over two of the rings 8. The sides of the retaining device rest on top of the spring fabric except that they project under the cross links marked 6^a for convenience of reference. The sides of the retainer are slightly bowed to give it additional longitudinal resilience. Secured to the arms of the wire 21 by means of any suitable form of clips 24 is a second hook 25, which is in line with the hook 23.

From the foregoing description, it will be obvious that when the head-rest is in lowered position, as shown in Figure 1, the bail 20 is in folded position under the head-rest and that when the head-rest is in elevated position, as shown in Fig. 3, the cross bar of the bail 20 engages in one of the hooks 23 or 25 depending upon the degree of inclination desired by the user of the bed. It will be observed that the head-rest is supported entirely by the spring structure so that the head-rest is adapted to move with the spring structure thus adding to the comfort of the user. The retaining device is extremely 100

cheap and readily secured in position on the bed, and at the same time affords the desired adjustment of the head-rest.

Referring now to Fig. 4, it will be obvious that in this view I have shown my invention applied to a spring structure comprising the usual coiled bed springs 27 connected by longitudinal and cross wires 28 and 29 and having the usual border wire 30. The head-rest and wire retaining device are the same as those described above. The head-rest is pivoted to the cross wire 29a and the retaining device is also secured to this cross wire. The cross wire 29a is provided with bends 31 adjacent the eyes 18 on the head-rest to prevent lateral sliding or displacement of the latter. The sides of the retaining device rest upon the spring structure except where they project under the top coil of the spring 27a. It will be obvious that the operation of the head-rest and retaining device shown in Figure 4 is the same as when applied to the wire fabric, as above explained.

I have shown a modified form of the retaining device in Fig. 2 in which it will be noted that the two hooks 23a and 25a are formed by suitably bending the single wire comprising the retainer. The manner of shaping this wire is clearly shown in Fig. 2 and requires no description.

I claim:

1. In a bed, the combination of a spring structure, a head-rest pivoted thereon, a supporting device for the head-rest, and a retaining device formed of a single piece bent to provide arms joined together at one end by a hook portion, said arms being mounted on the spring structure independently of said rest, said hook being adapted to be engaged by said supporting device to hold the head-rest in elevated position.

2. In a bed, the combination of a spring structure, a head-rest pivoted thereon, a supporting device for the head-rest, and a V-shaped wire having its ends secured to the spring structure and provided with an integral hook adapted to be engaged by said supporting device to hold the head-rest in elevated position.

3. In a bed, the combination of a spring structure including connected wire members, a head-rest, a supporting device for the head-rest, and a retaining device comprising a V-shaped wire having its ends secured to certain of said wire members and its side arms extending under other of said wire members and provided with a hook adapted to be engaged by said supporting device to hold the head-rest in elevated condition.

4. In a bed, the combination of a spring structure, a head-rest pivoted thereon, a supporting device swingably mounted on the head-rest, and a V-shaped wire having its arms bowed and its ends secured to the spring structure, the wire adjacent this V-end being

provided with a hook-like projection, said supporting device being adapted to be swung to a position to engage and be confined by said projection to hold the head-rest in elevated condition.

5. A structure for supporting a pivotally mounted head-rest in elevated condition upon a bed spring which comprises a member pivotally secured to the head-rest and having a transverse free end portion, and a V-shaped wire secured to the bed spring and having its arms bowed and its V-end bent to receive and embracingly confine the transverse end portion of said member.

6. A device adapted to be adjustably associated with a head-rest for a bed for supporting the head-rest in elevated condition which takes the form of a piece of wire bent to a V-shape with its V-arms bowed and its V-end bent back upon itself to form a hook, said V-shaped wire being stationarily supported by the bed.

7. In a bed, the combination with a spring structure, a head-rest pivoted thereon, and a supporting bail pivoted on said head-rest; of a wire-retaining device having its center part bent to form a hook open toward the pivoted side of said head-rest, said device being secured to said spring structure intermediate the edges of the latter and adjacent said head-rest, said hook being adapted to be interlockingly engaged with said bail to hold the head-rest in elevated position.

8. In a bed of a character having a spring structure including connected wire members, a head-rest pivoted directly on said spring structure; means for holding said head-rest in elevated condition which comprises a member pivoted to said head-rest and adjustable to swing the head-rest about its pivotal support, and a retaining device comprising a wire having integral eyes at its ends by which the device is secured to certain of said connected wire members and having a hooked mid-portion opening toward the pivoted end of the head-rest adapted to be engaged by said members to hold the head-rest in elevated position.

9. In a bed, the combination with a spring structure, a head-rest pivoted thereon, and a supporting device pivoted on the head-rest; of a single head-rest positioning device formed of wire, resting on and secured at its ends to said spring structure so as to yield independently and as a unit therewith, said positioning device having a plurality of projections at its mid-portion shaped to embracingly engage said supporting device to hold the head-rest at both of its sides in desired elevated position relative to the yielding spring structure, said supporting device once engaged being releasable only by movement of its engaged end a substantial distance toward said head rest.

10. In a bed, the combination with a spring

structure, a head-rest pivoted thereon, and a supporting device on the head-rest; of a retaining device comprising a one-piece wire having its ends secured to said spring structure so as to yield independently and as a unit with the spring structure, said wire being bent at a point intermediate its ends to provide a plurality of hooks adapted to be selectively engaged by the supporting device to simultaneously hold both sides of the head-rest in different elevated positions relative to the spring structure.
